EDGAR B. ULLMAN, EUGENE B. SIMMONDS, AND ARTHUR F. ATKINSON, OF MUNCIE,
INDIANA; SAID SIMMONDS ASSIGNOR OF ALL HIS RIGHT TO SAID ATKINSON.

HEAT AND VAPOR BATH CABINET.

1,346,353.

Specification of Letters Patent. Patented July 13, 1920.

Application filed September 16, 1918. Serial No. 254,354.

To all whom it may concern:

Be it known that we, EDGAR B. ULLMAN, EUGENE B. SIMMONDS, and ARTHUR F. ATKINSON, citizens of the United States, residing at Muncie, Delaware county, and State of Indiana, have invented and discovered certain new and useful Improvements in Heat and Vapor Bath Cabinets, of which the following is a specification.

Our invention relates to applicators such as heat and vapor cabinets, and the objects of our invention are to provide a device of this class in which the heating effect is obtained without the creation of fumes or gas from the heating appliance, and in which the heat generated is effectively utilized to its fullest extent; in which the heating medium is provided by a self contained electric unit which may be readily moved and easily disconnected from the body of the cabinet, and whereby means for supplying vapor to the cabinet and means for heating the interior thereof with dry heat may be connected to separate heating units so that either of said means may be employed separately, or both in conjunction.

With these objects in view, our invention is embodied in preferable form in the construction and arrangement hereinafter described and illustrated in the accompanying drawings.

In these drawings, Figure 1 is a perspective view in elevation of the cabinet body; Fig. 2, a vertical longitudinal section, and Fig. 3, a horizontal section, and Fig. 4, a detail vertical section of the steam generator.

Referring to the drawings, 1 indicates the cabinet which is of a form and size adapted to receive the body of a person when stretched at full length and which is adapted to be closely sealed and is provided at one end thereof with an opening 2, through which the head of the patient is projected and which opening is adapted to be closed preliminary to the treatment by means of a hinged door 3, adapted to fold down upon a bracket 4 in order to constitute a head rest. The cabinet is provided with a hinged lid 5 having a beveled upper surface. Legs 6 are provided at the corners of the cabinet for holding the same elevated above the floor. The bottom of the cabinet is made of sheet metal and slopes slightly from the ends and sides toward the center thereof

where it is tapped to receive a drain pipe 7. Mounted above the bottom is a slatted body support or bed 8 which is preferably curved downwardly toward the center of the cabinet from each longitudinal side 60 border thereof. One side of the cabinet is divided and hinged to permit the ready entrance of the patient.

Between the supporting bed and the bottom of the cabinet extends a coil or frame 65 of heating pipes 6, 10, 11 and 12, which are connected, and which at one end communicate with an inlet pipe 13, and at the other end communicate with an outlet 14 open to the atmosphere. These pipes are 70 adapted to receive steam and are adapted to raise the temperature of the air and vapor within the cabinet to the desired point by radiation therefrom. To this end the inlet pipe is connected to a steam generator 75 comprising a sheet metal water container or tank 15, by means of an intermediate pipe 16 having a slip joint at the point of connection with the radiating pipes. This member constitutes a self contained 80 steam generator, and to this end it is provided with an electrical heating unit 17 immersed in the water with which the tank is adapted to be supplied, and which device may be of any standard immersed electric heating unit. This heating unit is provided at its lower end with a tube or pipe section 18 which is threaded into the bottom of the container and through which pipe the conductor wires 19 leading from a 90 suitable source of electrical energy to the resistance elements of the heating unit are passed. Leading into the bottom of the tank of the generator is a filling and indicating pipe 20, which extends upwardly 95 exterior of the tank and terminates at its upper end substantially at the level of the water in the generator, and which end is open or adapted to be closed by a readily removable cap so that the corresponding 100 height of the water in the generator may be determined from an inspection of the level of the water in this filling pipe.

The tank of the steam generator is provided with a slip cover 21 adapted to fit 105 within the upper end of the tank and having an exterior rounded top. Within this top is provided a conical false top or plate 22 adapted to form a dead air space between the same and the outer curved top, and to 110

- form within the same a steam confining and directing chamber 23, the shape and area of which contribute to the ready generation of the steam within the tank and which serves 5 to direct the steam to the central part thereof of where the cover is connected to an elbow of the connecting pipe 16. By this arrangement a confined steam space is provided above the water in the tank and the generation 10 thus facilitated, and the same properly directed to the conveying pipe.

Mounted within the cabinet, preferably between the section of the radiating pipes, is a vapor conveying pipe 24 which pipe is 15 perforated throughout that portion thereof which lies within the cabinet in order to permit the escape of the vapor to the interior of the latter.

This pipe communicates with a generator 20 unit adapted to contain sulfur and water, or suitable medicaments adapted to the treatment which may be applied in particular cases, and such generator consists of a container 25 and electrically immersed heating unit 26, both similar to the corresponding elements described in respect to the self contained steam generator connected to the radiating pipes.

Heretofore, in cabinets of this general 30 class, it has been the usual practice to provide hot air heating units for the cabinets with the heat usually generated by a gas burner, and in which constructions a separate furnace and separate boiler are required. In these constructions, or those of 35 similar type, frequently the fumes and gas escape into the cabinet to the detriment of the therapeutic treatment, and also the presence of the fumes and gas in the room occupied by the cabinet is highly objectionable. 40 Moreover, such constructions usually require separate heat and steam generating units and are not readily portable and separable. In devices of this class it is highly 45 important not only that a pure condition of the air be maintained in a surrounding cabinet, but also that the heating unit be capable of being readily handled, moved and attached to or detached from the cabinet. This 50 result is accomplished in our invention by providing a self contained steam generator comprising a liquid containing tank and the electrical immersed heat unit which as an

entirety may be readily lifted and which owing to the slip connections with the cabinet may be readily detached therefrom and moved from place to place, and in which the heat within the cabinet is produced solely by the radiation from the steam pipes in conjunction, when desired, with such heat as 60 may be provided by the medicated vapor through the central pipe.

Having thus described our invention, what we claim is:—

1. In an applicator a vapor generator and 65 heater comprising a receptacle, a compartment formed within the receptacle with communication established between such compartment and the under side of the receptacle, a heating unit disposed within the 70 compartment, and a conduit leading from the receptacle to the applicator.

2. In an applicator a vapor generator and heater comprising a receptacle, a compartment erected within the receptacle and 75 closed wholly upon those surfaces located within the receptacle but communicating through the bottom of the receptacle, a heating unit located within the compartment, energizing means for the heating unit ex- 80 tending through the opening in the bottom, and a conduit leading from the receptacle to the applicator.

3. In an applicator a vapor generator and 85 heater comprising a receptacle, a heating unit erected within the receptacle and having an outlet only through the bottom of the receptacle, energizing conductors leading into the compartment through the opening in the bottom, a heat insulating cover member positioned over the top of the receptacle, a conduit forming communication between the receptacle and the applicator, and means 90 to introduce water into the receptacle without removing the insulating cover.

In witness whereof we have hereunto set our hands and seals at Muncie this 9 day of September, A. D., nineteen hundred and eighteen.

EDGAR B. ULLMAN.
